UNITED STATES PATENT OFFICE

137,812

DESIGN FOR AN AMPHIBIAN TANK OR SIMILAR ARTICLE

George Francis Myers, Jackson Heights, N. Y.

Application October 18, 1940, Serial No. 95,915

Term of patent 3½ years

(Cl. D14—3)

To all whom it may concern:

Be it known that I, George Francis Myers, a citizen of the United States, residing at 3516 80 Street, Jackson Heights, in the county of Queens and State of New York, have invented a new, original, and ornamental Design for an Amphibian Tank or Similar Article, of which the following is a specification, reference being had to the accompanying drawings forming part thereof.

Figure 1 is a side elevational view of my new design of an amphibian tank with the water wings or floats retracted.

Fig. 2 is a front elevational view showing the

water wings or flotation gear inflated and expanded.

Fig. 3 is another front elevational view with the water wings deflated and retracted.

Fig. 4 is a top plan view of the vehicle showing the water wings expanded as in Fig. 2.

Fig. 5 is another top plan view with the water wings deflated and retracted as in Fig. 3.

I claim:

The ornamental design for an amphibian tank or similar article, as shown and described.

GEORGE FRANCIS MYERS.
